UNITED STATES PATENT OFFICE.

BURCHARD THOENS, OF NEW YORK, N. Y.

COTTON-GIN.

No. 876,412.

Specification of Letters Patent.

Patented Jan. 14, 1908.

Application filed May 22, 1906. Serial No. 318,206.

To all whom it may concern:

Be it known that I, BURCHARD THOENS, a subject of the Emperor of Germany, residing at New York, in the county of New York and 5 State of New York, have invented certain new and useful Improvements in Cotton-Gins, of which the following is a specification.

My invention relates to cotton gins and 10 consists essentially in providing a series of fixed bars and intermediate movable bars by which the fibers of the cotton can be gripped, and blades by means of which the cotton and seeds outside the bars may be carried therefrom, together with details of construction 15 fully set forth hereinafter and illustrated in the accompanying drawings, in which,—

Figure 1 is an elevation in part section of a cotton gin embodying my improvements, 20 showing one form in which the same may be employed; Fig. 2 is a transverse section on the line 2—2, Fig. 1; Fig. 3 is a section illustrating another form in which my improvements may be embodied; Fig. 4 is a view 25 illustrating different arrangements of fixed and movable bars; and Fig. 5 a view illustrating another arrangement of the said bars.

The essential features of the apparatus 30 embody gripping members of any suitable shape and arrangement, that may be separated so as to allow the tufts of cotton to pass between them, preferably by the action of air currents, and then brought together to 35 grip the fibers, and a wiping member or members consisting of a blade or contact piece of any suitable character which, after the fibers are gripped by the gripping members, will take hold of the remaining fibers or seed 40 and drag the same from the grippers, which are subsequently separated to permit the fibers to pass from between them, either by the action of the air currents or brushes, or otherwise. The grippers may be moved in 45 respect to stationary wipers, or the grippers may be held relatively stationary, and the wipers moved.

In the construction shown in Fig. 1 there 50 is a casing A the top of which is composed of alternate strips 2, 3, the strips 2 being secured to the casing, while the strips 3 are carried by spring blades 10 pendent from a reciprocating frame B, the movements of which carry the strips 3 back and forth between the strips 2, 2. Preferably the strips

have rubber facings 9 and they are of such width that when a strip 3 is moved laterally into contact with one of the strips 2, the distance between the strip 3 and the other strip 2 will be less than the diameter of the cotton 60 seeds so that the latter cannot pass between the strips.

The operation of the frame B causing the strips 3 to move back and forth between the strips 2, may be effected in any suitable way. 65 As shown, an arm at each side of the frame carries a square bracket C with anti-friction rolls with which contacts a cam or eccentric 7 on a rotating shaft 13, but any other suitable means of reciprocating the blades may 70 be used.

Over the faces of the bars 2, 3, when the latter occupy a relatively stationary position, as in the construction of Figs. 1 and 2, moves a wiper or wipers D, each of which, as 75 shown, consists of a serrated blade, the toothed edge of which travels in close proximity to the bars 2, 3. In the construction shown in Figs. 1 and 2 where there is a series of blades the same are carried by the links of 80 chains 15 which pass beyond the casing A over suitable sprockets 16, upon shafts 17, turning in bearings on the frame E, and the casing A is supported by the said frame between the upper and lower portions of the 85 chains, and is closed except that the air may pass between the bars or slats 2, 3 to enter the interior of the casing and to an outlet x communicating with a fan or other exhausting apparatus, X, Fig. 1. 90

In the operation of the device the cotton is fed from a hopper Y and passes to the surfaces of the bars 2, 3, and is carried over the same by the blades or wiping members D, the gripping members 3 moving back and 95 forth between the fixed members 2. As the result of this operation the fibers of the cotton adhering to the seeds will be carried between the separated members 2, 3 by the air currents and will then be gripped as these 100 members change their position, and while the fibers are thus gripped the wiping members, by contact with the ungrasped portions of the cotton and seeds, will carry the latter away from the gripped fibers, breaking the 105 connection between the two, and on the separation of the members 2, 3 the fibers thus separated from the mass will be carried into the casing and away by the air current, and the masses of the fiber and seed outside the 110

casing will pass onward and other fibers will be gripped and separated and carried away until each seed has so little fiber adhering thereto that there will be nothing to be gripped by the gripping members.

It will be evident that there may be different arrangements of the gripping members. As shown in Fig. 3, these members are arranged so that the casing is cylindrical, the members or bars 2 being secured to the heads 19 of the casing, while the bars 3 are connected with spring blades 20 secured to disks 21, which are caused to oscillate by the action of cams 22 on a shaft 23 bearing on friction rollers carried by gears 24 of the disks 21. The wipers D, in this case, are carried around the cylinder and within a perforated casing 25, the action being the same as in the construction illustrated in Figs. 1 and 2. In the construction shown in Fig. 4, the gripping members are annular, the movable members 3, playing back and forth between the members 2, 2, and in Fig. 5, the moving member tilts between the fixed members 2, 2; but it will be seen that in any event there is no cutting of the fibers and but little tendency to tear the same, these effects being further reduced by the facing of elastic or flexible material upon the gripping members, and it will be seen that as soon as the fibers are separated from the seed and ungripped they are carried away.

It will be seen that in Figs. 1, 2 and 3 the reciprocating bars or members are connected to the moving part by means of flexible arms or springs whereby, in case of any cotton or seed being jammed between the bars the latter are prevented from crushing the same.

It will be seen that it is immaterial whether the wiping members are movable over the gripping bars, or the wiping members are stationary and the gripping bars carried below the same.

Without limiting myself to the construction and arrangement shown, I claim as my invention:

1. In a cotton gin, the combination of gripping members arranged to support the seed without permitting it to pass between the same and means for separating and bringing them together to grip the cotton, and wiping members whereby the seeds are carried from the gripping members.

2. In a cotton gin, the combination of gripping members arranged to support the seed without permitting it to pass between the same and means for separating and bringing them together to grip the cotton, wiping members whereby the seeds are carried from the gripping members, and a port and means for drawing an air current through

said port to carry the fibers, when released from the gripping members.

3. A cotton gin provided with a hollow cylinder composed of a series of pairs of separable gripping members, means for separating and bringing said members together, to pinch the fibers between them and wiping members whereby the seeds are separated from the cotton gripped by the gripping members.

4. A cotton gin provided with a casing having separable gripping members with elastic facings, means for separating and bringing said members together, and wiping members whereby the seeds are separated from the cotton gripped by the gripping members.

5. A cotton gin provided with a casing having series of pairs of separable gripping members arranged to form spaces when separated less in width than the diameter of the seeds, means for positively separating and bringing the members of each pair together, and wiping members whereby the seeds are separated from the cotton gripped by the gripping members.

6. The combination in a cotton gin, of a stationary casing provided with a series of fixed bars and a series of movable bars, means for reciprocating the latter, blades and means for carrying them over the bars, and means for exhausting the air from within the casing, substantially as set forth.

7. The combination in a cotton gin, of a casing provided with a series of fixed bars and an intermediate series of movable bars, and springs connecting the said movable bars to a reciprocating frame.

8. The combination in a cotton gin, of a casing having fixed and movable bars, and means for reciprocating the latter through the medium of a yielding spring connection.

9. In a cotton gin provided with a casing having a series of fixed and movable bars, means for reciprocating the latter, and traveling chains supporting blades to carry the same over the movable bars.

10. The combination in a cotton gin, of a fixed casing, a series of fixed and movable bars at the top thereof, a reciprocating frame provided with blades connected with the movable bars, and chains supported by sprockets and supporting blades to carry the same over the faces of the bars.

In testimony whereof I affix my signature in presence of two witnesses.

BURCHARD THOENS.
